UNITED STATES PATENT OFFICE.

WILLIAM N. SEWELL, OF WINCHESTER, KENTUCKY.

RAILWAY RAIL AND TIE.

1,282,647.

Specification of Letters Patent.

Patented Oct. 22, 1918.

Application filed April 10, 1916. Serial No. 90,169.

To all whom it may concern:

Be it known that I, WILLIAM N. SEWELL, a citizen of the United States, residing at Winchester, in the county of Clark and State 5 of Kentucky, have invented certain new and useful Improvements in Railway Rails and Ties; and I do hereby declare the following to be a full, clear, and exact description of the invention, such as will enable others 10 skilled in the art to which it appertains to make and use the same.

This invention relates to metallic railways, and the object of the same is to produce a metallic railway consisting of compound 15 rails, in combination with metal cross-ties carrying rail-clamps and retaining keys for the purpose of securing and retaining the component parts of the compound rail in assembled position and on the cross tie with- 20 out the use of fish plates, bolts or spikes. The compound rail is made up of a number of pieces and may be constructed in a variety of types, some of which are illustrated in the drawings and described in detail be- 25 low; but the underlying principle is the use of hardened metal for the upper part or tread of the rail so as to reduce the wear thereon, and cheaper but tough metal for the core and base of the rail where the contact 30 of the car wheels does not produce wear. Several means are shown for fastening the parts of the rail together and to the tie; and for details of my preferred manner of carrying out this invention reference is made to 35 the following specification and claims, and to the accompanying drawings wherein:—

Figure 1 is a perspective view of one type of this rail with its forward end in section, showing it as fastened to one type of my im- 40 proved tie which is also in perspective; Fig. 2 is a longitudinal section through the tie and through a rail of another type; and Fig. 3 is a similar section showing a rail of still a third type.

Figs. 4 and 5 are perspective details re- 45 spectively of the insulation pad and the shoe which underlies it, these parts being shown in section in their proper position in Fig. 3.

Fig. 6 is a perspective view of one member 50 of the two-part tie, and Fig. 7 a plan view showing the two members thereof interengaged, while Fig. 8 is a cross section on the lines 8—8 of Fig. 7.

Figs. 9, 10, 11 and 12 are perspective de- 55 tails of various forms of fasteners used in

connection with the cross tie and compound rail.

Figs. 13, 14 and 15 are perspective views of the several members of a three-part tie, and Fig. 16 is a plan view showing these 60 members interengaged, while Fig. 17 is a cross section on the line 17—17 of Fig. 16.

Fig. 18 is a plan view showing how my tie may be employed for holding two rails which stand alongside each other and slightly out 65 of parallelism.

The rail forming an important feature of the present invention is designed to be supported upon a metal tie made in two or more members S and T slidably mounted on each 70 other and held relatively in working position by a key K, the members having openings O in which are mounted fasteners F to engage opposite sides of the rail to secure the members thereof in assembled position and 75 to fasten the rail to the tie in a manner more fully explained below. Said fasteners may also take the shape shown at F' or F² in order to adapt them to the modified forms of rail, or the shoe or insulating pad or both 80 with any type of rail; and, as described below, these fasteners alone are sufficient to hold the parts of the rail together as well as holding the rail on the tie.

The type of my improved rail shown in 85 Fig. 1 comprises a core of tough metal and a tread and casing of hardened metal. The core includes an upright web 1 having a base 2 across its lower edge, an enlarged bead 3 just above said base, and an enlarged head 4 90 along the upper edge of the web provided in

its upper face with a V-shaped channel 5— all being in one piece of tough metal. The other member of hardened metal is made in two complementary parts. Each part in- 95 cludes a tread 6 having a depending under- cut lip 7 beveled along its lower face to fit one wall of the channel 5, a flange 8 lying alongside the web 1 and out-turned as at 9 to fit closely over the bead 3, and a base 100 which may include a flange 10 overlying one side of the base 2 and a foot 10' along its outer edge resting on the tie. The parts of

this rail are assembled as shown, and when the fasteners F are brought against the outer 105 edges or feet 10' of the two bases 10, all parts of the rail are pressed into close relation with each other and borne downward onto the upper face of the tie. The load thrown upon this rail by the pressure of wheels on 110

its tread causes the two lips 7 to bear downward against the walls of the V-shaped channel 5 and, if anything, to move inward toward each other. As shown in Fig. 1, the 5 two parts of the tread-member may be laid so that their extremities meet each other on lines which break joint, and by this means a continuous rail is produced.

The type of my improved rail shown in 10 Fig. 2 has a web 11, a base 12, beads 13 on the web somewhat above the base, a head 14 and a V-shaped channel 15—all made of 15 tough metal. The other member is here made in four parts—two tread parts which must be of hardened metal, and two other parts constituting the casing and which may be of either hard or soft metal. Each tread 16 has a lip 17 and a flange 18, the latter out-turned at its lower edge as at 19 and 20 resting on the upper side of the bead 13. Each of the other parts has a base 20, a flange 18' rising therefrom and out-turned as at 19' to pass around the bead 13, and an inturned portion or hook 19'' along its 25 upper edge to engage the out-turned portion or hook 19. The fasteners F' used with this type of rail should not only clamp the bases 20 on the base 12, but should also rise high enough to hold the hooks 19 and 19'' in 30 engagement with each other as shown.

The type of my improved rail shown in 35 Fig. 3 comprises a web 21 with a base 22, and a head 24 with a V-shaped channel 25, and beneath said head the web has through it a hole 23. The hard metal member is again in two parts, the treads 26 having lips 27 and flanges 28; but instead of using beads on the web and out-turned portions on the other member to engage them, I here employ 40 bolts 29 passing through the flanges 28 and the hole 23 in the interposed web. In this construction the web will therefore preferably be made somewhat heavier than in the types above described, because the core 45 of the rail is not entirely incased.

Any type of my improved rail may be insulated from the tie by the use of the members shown in Figs. 4 and 5, and although I have shown these members as applied in 50 Fig. 3 only, it will be understood that they could be used in Figs. 1 and 2 if the engaging faces or notches of the fasteners were appropriately formed. The insulating device includes a pad or preferably a pair of 55 pads 30 turned up at their outer edges as at 31 to pass over the edges of the base, whether such base be that of the core or the base flanges or feet of the casing; and if two such pads are used they should nearly meet 60 beneath the base as seen in Fig. 3. They are by preference inclosed within metallic shoes 32, each of which is also upturned at its outer edge as at 33 to inclose the upturned edge of the pad and to protect the latter 65 from the overhanging portion of the fas-

tener. The tie will have an opening or a slot 34 extending transversely beneath the base of the rail, and in order to prevent the shoes from moving longitudinally of the rail they may be provided with depressed 70 tongues 35 which will pass into this slot as seen. These shoes may be made of sheet metal and stamped into the shape shown in full lines in Fig. 5, or they might be cast if preferred, and—as above suggested—the 75 fasteners will be adapted to fit the shoes. With the use of this insulating device no metal part of the rail touches any part of the tie or its fastener, and this is sometimes considered highly desirable in electric 80 railway construction.

The type of my improved tie and fastener shown in the accompanying drawings is particularly adapted for use with a compound rail as above described, and avoids 85 the necessity for fish plates, bolts, and spikes. The tie is made in two complementary and like members, one of which is shown in perspective in Fig. 6. It may well be stamped from metal rolled or bent into the form 90 illustrated, and two of these members are shown engaged with each other in Fig. 7. Each comprises a flat bottom plate 40, bent up at about right angles into a web 41, and then bent again inward at about right angles 95 into a top 42. The inner edge of this top is cut at about its center with an opening 43 and near each end with a bayonet opening 44, thereby dividing the inner edge 100 of the top into four parts whereof those numbered 45 are bent up slightly and those numbered 46 are bent down slightly so that when the two members are engaged these parts pass each other as seen in Fig. 8. Each part 46, just behind the wider end or "heel" 105 of the bayonet opening, is provided with a socket 47, shown in Fig. 6 as a slot extending longitudinally of the top 42; and the spur 48 at the other or "toe" end of the opening 44 projects toward this socket, the 110 parts being of such width that (as seen in Fig. 1) the spur is adapted to pass freely behind the fastener in the socket in the companion member, and said fastener is narrower than the toe end of the opening 44. 115 Near each end of the top 42 is an inclined slot 49, and adjacent one or both of these slots may be additional and like slots 49' for a purpose yet to appear.

The two members of this tie are assembled as seen in Figs. 1, 7 and 8 beneath a compound rail as indicated in dotted lines at R, and in each socket 47 is placed a fastener F of suitable shape. Referring to 50, Fig. 9, this fastener has at its inner end a jaw 51 at the top, a spur 52 at the bottom, and a notch 53 between them, while its rear end has a lug 54 at the top with a notch 55 beneath it. The spur is passed down through the toe of the bayonet opening 44 and into 130

the socket 47, and the lug overlies the top plate 42 at the outer end of the socket while the jaw 51 overlies the base of the rail and the notch 53 engages the edge of said base, 5 as in Fig. 1. The slots 49 of the two members are placed in registry with each other and keys K are inserted in them as best seen in Fig. 1, their lower ends being brought out through side openings K', Figs. 10 1 and 2, and bent to hold them in place. If a rail of wider base is to be used and it is desired that the two sockets 47 should stand a little farther from each other, the additional slot 49' on one member may be 15 brought into register with the slot 49 on the other for the reception of the key; although of course the same result would be obtained by using a shorter fastener. When now the tie-sections are separated 20 slightly by placing material between their upright webs and tamping it in place, the inclination of said slots causes them to move along the keys obliquely with reference to each other and in such direction that the 25 two fasteners are forced toward each other and their jaws forced against the edges of the base of the rail; and the greater the pressure on the rail and tie, tending to separate the members of the latter, the more 30 tightly these fasteners will grasp the rail.

A special form of fastener is shown in Fig. 10 at 56. This has jaws at both ends, and its spurs 57 project laterally, and it is useful for interposition between two adjacent rails as seen in Fig. 18. When, for instance, two rails approach a switch, the members of the tie may be lengthened at one end and provided with additional sockets 47. In this view both of such sockets 40 are shown as containing fasteners 50, and the special fastener 56 stands between them. Its position is indicated in dotted lines in Fig. 7. When the tie-members are put together it will be obvious that the heel ends of the two bayonet openings will register as shown at 58 in this view and a fastener with lateral spurs 57 can be passed through the registering openings as shown by the dotted lines. Thereafter the relatively end- 50 wise movement which brings the two fasteners 50 against the two rails R in Fig. 18, will reduce the size of the opening 58 and engage the spurs under the top plates 42, and the two jaws at the upper end of the 55 special fastener 56 will engage the contiguous flanges at the base of the two rails.

The type of my improved tie and fastener shown in Figs. 11 to 17 is made of three members, one of which may be long enough 60 to reach beneath both rails while each of the other two is long enough to reach beneath one rail and carry two fasteners and a key. This modification of the tie in combination with the compound rail also avoids the necessity for fish plates, bolts, and spikes; and,

like the other, it can be made of sheet metal or rolled or cast. The two ends of the long member may be alike and the two short members like each other, but I have made use of Figs. 13, 14 and 15 to show different 70 forms that are possible. Here again each member comprises a flat bottom plate 60, an upright web 61, and a top plate 62, and the meeting edges of the top plates of two members are bent up and down at points so as to 75 interengage as above described. Referring first to the construction shown at the left of Figs. 13 and 16 and in Fig. 14, the members have openings 63 to engage each other loosely and inclined slots 69 which register 80 for the the reception of a key when the members are spread apart. Said members also have bayonet openings 64 whose spurs 68 are cut off oblique at their inner ends as seen at 65. I have used these views to show 85 how one fastener 66 might be formed integral with the top plate 62 and bent up opposite the heel end of its bayonet opening 64. The other top plate is provided with a longitudinal socket adjacent the heel end of its 90 bayonet opening, as shown at 67 in Fig. 14. This socket is to receive the fastener 70 shown in Fig. 12, such fastener having a jaw 71 and longitudinal spurs 72 and 73. The parts are shown assembled at the left 95 end of Fig. 16, but they have not yet been spread apart and therefore the fasteners do not yet engage the base of the rail which latter is indicated by the dotted lines R. I have also made use of these views to show 100 stops 74 which may be bent up from the top plate behind the toe end of each bayonet opening. These stops approach the base of the rail as the fastenings recede from it, and they therefore prevent displacement of the 105 rail when the fastenings are not engaged with its flanges, and also they prevent the rail from sticking under the jaws of the fastenings when it is to be lifted out of place. These stops may be used in other 110 types or forms of my invention. Also, while I have shown but one fastening bent up at 66, both might be so formed; and while I have shown only one member provided with a socket 67 for a separate fastening 70, both 115 members might be so formed—much as is the construction of the tie shown in Figs. 6 and 7. With the parts assembled as seen at the left of Fig. 16, when the members are spread apart until the slots 69 register for 120 the reception of the key, the oblique ends 65 of the spurs slip past the outer ends of the fastenings so that the latter are simultaneously moved inward and into engagement with the flanges of the rail base; and finally 125 the insertion of the key in the registering slots 69 locks the parts in this position.

A slightly different form of this modification of the tie and fastener is shown at the right ends of Figs. 13 and 16 and in 130

Fig. 15. Here the two openings 83 interengage, as do the two openings 84, and the openings 89 which eventually receive the key. Both members have sockets which 5 may be in cross form as shown at 85 or of T-shape as shown at 86, and when the members are engaged these sockets overlap each other and their lateral openings admit cross spurs 77 on fasteners 76 as shown in Fig. 10 11, after which the endwise movement of the members engages these spurs beneath their top plates. The members must now be moved longitudinally upon each other to force and hold the jaws of the fasteners 15 over the flanges of the rail base or against opposite sides of the compound rail, and this is done by driving a tapering or wedge-shaped key K^2 down into the openings 89, which now register as seen in Fig. 16. Obviously this key could be made wider or 20 narrower to accommodate a rail having a wider or narrower base, or to permit the use of the insulating device above described; and also the key for the slots 69 could be made 25 of different thickness for the same purpose.

The fundamental principle underlying the action of all types and styles of my improved tie is that after the interengagement of the two members, they are moved upon 30 each other slightly to cause the jaws of the fasteners to engage opposite sides of the rail. At the right end of Fig. 16 this movement results from sliding the members longitudinally of each other. This is done 35 by driving in the key K^2 , which may be then held by bending out its lower end as indicated at k^2 . The fasteners—or at least one of them at each point of fastening—may be integral with the tie, but I prefer to make 40 them separate therefrom so as to adapt the device to compound rails with bases of different width. In all cases, however, the fasteners stand in a plane or planes strictly parallel with the length of the tie, and their 45 movement into locking position is on lines straight toward the rail. In the modification shown in Fig. 16, one of the short members can be inserted beneath and removed from one rail without interfering with the 50 other short member or the long member, and at times this may be very important as when the other end of the long member passes under a frog or is perhaps extended clear across beneath a third rail and it is not desired 55 to disturb it.

What I claim is:

1. In a metallic railway, the combination of a compound rail comprising a web having a base, a tread divided in two parts on 60 an upright line above and coacting with the top of the web, and a sectional tie having means for fastening said parts against opposite sides of the web.

2. In a metallic railway, the combination 65 of a compound rail comprising a web having

a base, a tread divided in two parts on an upright line above and coacting with the top of the web, flanges depending from said parts alongside the web, a sectional tie, and fastening means thereon for holding the 70 tread parts in contact with the base.

3. In a metallic railway, the combination of a compound rail comprising a web having a base, a tread divided in two parts on an upright line above said web and each part 75 having a lip with the lower face coacting with the top of the web, flanges depending from said parts alongside the web, a tie comprising complementary sections, and fasteners for holding all the rail parts in 80 place without extraneous fastening.

4. In a metallic railway, the combination of a compound rail comprising a web having its lower edge enlarged into a base and its upper edge enlarged into a head, a tread 85 in two parts, each shaped to include one half of said head and a lip with a lower face to rest on said head, and a flange depending alongside the web, a tie upon which said base is disposed, and means engaging the 90 tie for fastening said parts against the web and preventing them from rising.

5. In a metallic railway, the combination of a compound rail, comprising a core member including a base, a web having laterally 95 projecting beads, and a head along the upper edge of the web provided with a channel; a second member made in two halves and constituting a tread and casing, the tread of each half having a lip engaging said channel, and the casing of each half out-turned to engage one bead and having a base engaging the base of the core member, a sectional tie on which said base rests, means interlocking with the tie for holding all parts of the rail, 100 and means for actuating and locking the tie sections together.

6. In a metallic railway, a compound rail, a core member of tough metal including a base and a web having laterally projecting 110 beads and a V-shaped channel in its upper edge; a second member made of hard metal and in two halves, each including an undercut lip to engage one wall of the channel, a flange out-turned to engage one of said 115 beads, and a part overlying one side of the base of the core member and having a foot along its outer edge; a metallic sectional tie, keys for locking the sections, and means carried by the sections of the ties for holding 120 all parts of the rail together thereat.

7. In a metallic railway, a railway tie made up of members having feet, webs, and top plates adapted to overlap each other, one of said plates having a socket and the 125 other a larger opening adapted to register therewith when said members are in one relative position, a rail on said tie, and a rail fastener for insertion through the socket and opening and having a spur at its lower 130

end whereby it is held in place when said members are in another relative position, and keys for locking the members in rail securing position.

5 8. In a metallic railway, a railway tie made up of complementary metal members having openings in their meeting edges and the parts between said openings bent upward and downward whereby the members are
10 adapted to interengage, one member having a socket and the other a larger opening adapted to register therewith when said members are in one relative position, a rail on said tie, a rail fastener for insertion
15 through the socket and opening and having a spur at its lower end whereby it is held in place when said members are in another relative position, and means for securing the rail members in position and causing them to
20 move endwise with the fastener.

9. In a metallic railway, a railway tie made in complementary metal members having bayonet openings and other openings in their meeting edges whereby they are adapted to be overlapped, each member having a socket at the heel end of its bayonet opening adapted to register with the toe end of the bayonet opening in the other member when said members stand in one relative position, fasteners for insertion in said sockets to be held therein when the members are moved to another relative position, a rail engageable by said fasteners, and means causing the members to move the fasteners to engage the
35 rail and for holding them in such position.

10. In a metallic railway, a railway tie made in complementary metal members having bayonet openings and other openings in their meeting edges whereby they are adapted to be overlapped, each member having a socket at the heel end of its bayonet opening adapted to register with the toe end of the bayonet opening in the other member when said members stand in one relative position, a rail, rail fasteners for insertion in said sockets to be held therein when the members are moved to another relative position, the members being provided with openings adapted to register when they are moved to

said second position, and a key for insertion 50 in these openings and adapted to lock the sections against movement.

11. In a metallic railway, a railway tie made in complementary metal members having bayonet openings and other openings in 55 their meeting edges whereby they are adapted to be overlapped, each member having a socket at the heel end of its bayonet opening adapted to register with the toe end of the bayonet opening in the other member when 60 said members stand in one relative position, a rail, rail fasteners for insertion in said sockets to be held therein when the members are moved to another relative position, the members being provided with openings 65 adapted to register when they are moved to said second position, and a key for insertion in these openings and adapted to lock the sections against movement, the key adapted to clench upon an adjacent part of the tie 70 to hold itself in position.

12. In a metallic railway, a railway tie made in complementary metal members having bayonet openings and other openings in 75 their meeting edges whereby they are adapted to be overlapped, each member having a socket at the heel end of its bayonet opening adapted to register with the toe end of the bayonet opening in the other member when said members stand in one relative position, 80 a rail, rail fasteners for insertion in said sockets to be held therein when the members are moved to another relative position, the members being provided with openings adapted to register when they are moved to 85 said second position, and a key for insertion in these openings and adapted to lock the sections against movement, the key having a shank insertible into a keeper portion of the tie and adapted to be bent into clenching position. 90

In testimony whereof I affix my signature in presence of two witnesses.

WILLIAM N. SEWELL.
